UNITED STATES PATENT OFFICE.

WALTER F. SCHELP, OF ST. LOUIS, MISSOURI.

DESIGN FOR A DOCUMENT, CONTRACT, OR OTHER LEGAL INSTRUMENT.

52,858.

Specification for Design.

Patented Jan. 7, 1919.

Application filed May 6, 1918. Serial No. 232,958. Term of patent 7 years.

To all whom it may concern:

Be it known that I, WALTER F. SCHELP, a citizen of the United States, residing at St. Louis, in the State of Missouri, have invented a new, original, and ornamental Design for Documents, Contracts, or other Legal Instruments, and of which the following is a specification, reference being had to the accompanying drawing, forming part thereof.

The upper left-hand corner is shown in detail and the other three corners diagram-

I claim—

The ornamental design for a document, contract, or other legal instrument, as shown,

WALTER F. SCHELP.
